UNITED STATES PATENT OFFICE.

JOSEPH CROSSLEY, OF TRENTON, NEW JERSEY.

DESIGN FOR A BRICK OR BUILDING-BLOCK.

SPECIFICATION forming part of Design No. 21,631, dated June 21, 1892.

Application filed May 23, 1892. Serial No. 434,111. Term of patent 7 years.

To all whom it may concern:

Be it known that I, JOSEPH CROSSLEY, a citizen of the United States, residing at Trenton, in the county of Mercer and State of New Jersey, have invented and produced a new and original Design for Building Blocks or Bricks, of which the following is a specification, reference being had to the accompanying drawings, forming part thereof.

10 Figure 1 is a perspective of my design, and Fig. 2 a vertical transverse section.

The leading feature of my design consists in a rectangular sunken panel or intaglio, in which the bottom of the panel is corrugated 15 transversely and the panel surrounded by a continuous margin or border.

A indicates a building block or brick oblong in form; B, a rectangular sunken or de-

pressed panel or intaglio, the bottom C of which is corrugated transversely, the corrugations being formed by longitudinal ribs or projections *a* and grooves *b*, and the panel is surrounded by a continuous margin or border D, which extends to the edges of the building-block. The panel is formed on both 25 sides of the block.

What I claim is—

The design for a building block or brick, substantially as herein shown and described. In testimony whereof I affix my signature in 30 presence of two witnesses.

JOSEPH CROSSLEY.

Witnesses:

WILLIAM J. CROSSLEY,
DAVID CROSSLEY.
